(57) **CLAIM**

The ornamental design for an angle tamper for asphalt, as shown and described.

DESCRIPTION

FIG. 1 is a front perspective view of an angle tamper for asphalt of my invention in use;

FIG. 2 is a top plan view of an angle tamper for asphalt of my invention based on FIG. 1;

FIG. 3 is a bottom plan view of an angle tamper for asphalt of my invention based on FIG. 2;

FIG. 4 is a side view of an angle tamper for asphalt of my invention based on FIG. 1;

FIG. 5 is a reverse view of FIG. 4;

FIG. 6 is a front elevation view of an angle tamper for asphalt of my invention based on FIG. 1;

FIG. 7 is a rear elevation view of an angle tamper for asphalt of my invention based on FIG. 6;

FIG. 8 is a front perspective view of an angle tamper for asphalt of my invention based on FIG. 1; and,

FIG. 9 is a rear perspective view of an angle tamper for asphalt of my invention based on FIG. 8.
